UNITED STATES PATENT OFFICE.

NELSON ELVIRUS HARRIS, OF ORANGE, MASSACHUSETTS.

HYDRAULIC MOTOR.

SPECIFICATION forming part of Letters Patent No. 337,766, dated March 9, 1886.

Application filed November 9, 1885. Serial No. 182,288. (No model.)

To all whom it may concern:

Be it known that I, NELSON ELVIRUS HARRIS, of Orange, in the county of Franklin, of the Commonwealth of Massachusetts, have 5 invented a new and useful Improvement in Hydraulic Motors, termed "Turbines;" and I do hereby declare the same to be described in the following specification, and represented in the accompanying drawings, of which—

10 Figure 1 is a vertical and transverse section of a turbine containing my invention, the nature of which is defined in the claims herein-after presented. Fig. 2 is a horizontal section taken through the water-wheel and its 15 chutes. Fig. 3 is a horizontal section of the gate, showing its feet or water-guides.

In the said drawings, A denotes the case, within which the gate c is arranged concentrically. The said gate has, as usual, machinery 20 for raising and lowering it, such machinery being on and extending above and partly through the said case, as in various other turbines. The gate has projecting from it, at its lower edge, a series of feet or water-guides, a', 25 each of which extends between and from one to the other of two of the chutes e, that are disposed at equal distances apart around the water-wheel B, and inclined or curved, as usual, to direct the water to the buckets or 30 floats of such wheel. These chutes are supported by two rings, b' and c', with which they are cast in one piece. The upper ring, b', is curved, as shown, on its lower surface, to aid in directing the water between the chutes. 35 The lower ring is a flat annulus, and is supported within a rabbet or recess, d', formed within a flange, e', projecting horizontally from the draft-tube C.

The water-wheel is composed not only of 40 an inverted bell-shaped body, b, and a series of wings or buckets, e², extending, at equal distances apart, down from such body and within the draft-tube, but of a vertical ring, f', that surrounds and is fixed to the parts of 45 the buckets which project within the draft-tube, all being as represented, and the ring being extended to the top of the lower sustaining-ring of the chutes.

Encompassing the gate and fastened to its 50 case A, and arranged therewith, as represented, is a flat ring, h', which has projecting

from its outer periphery a tongue, l', that extends into a corresponding rabbet or groove, m', formed in the top of the upper of the two chute-sustaining rings, such upper ring being 55 fixed to the lower part of the case A by a suitable number of screws, n'.

Resting on the top of the ring h', and circumscribing the gate, is another flat ring, o', whose inner periphery is grooved to receive packing 60 to fit to the gate. This ring o' is secured to the ring h' by a series of screws, p'. The wheel-shaft is shown at a. At its lower end the said shaft is provided with a tenon, f, that enters a chambered shoe or step, g, fixed to the shaft. 65 This shoe or step is conically recessed at its bottom, and there provided with a conical composition concavo-convex bearing, g', to receive and bear on the top of a wooden pivot, h, extending upward from and into a metallic 70 carrier, i. This carrier is arranged vertically in the eye of a spider, k, secured to and extending down from and within the draft-tube. The carrier i rests on a plate, i², supported by nuts m, screwed on bolts l, that go down through 75 such plate and the spider. Through such plate i² and the axis of the pivot is a passage, p", for the water to pass to the crown of the pivot-bearing.

By means of the pivot-carrier, its support- 80 ing-plate, and the bolts and nuts for sustaining such plate the wooden pivot may be ad-justed or moved upward from time to time as the bearing-plate q' may become worn. The shaft a passes through a stuffing-box, n, pro-jecting upward from the case A, and bolted thereto. On the top of the said stuffing-box, and concentric with the shaft, is an annulus, o, of wood or other suitable material, and di-rectly above and resting on the said annulus 85 is a metallic collar, p, that encompasses the shaft, it being fixed thereto by one or more set-screws, r, screwed into the annulus and against the shaft. From the above it will be seen that the said collar will revolve with and 90 be revolved by the shaft, and by resting on the annulus or bearing o will relieve the pivot and step of much, if not all, of the weight of the wheel and shaft, and thereby prevent to a great degree, if not entirely, wear of their 95 bearing-surfaces. As the wooden bearing o on the inner collar may become worn, the col- 100

lar may be adjusted so as to hold the step in light contact with the pivot, such collar being in a position above the water where access to it and its wooden bearing can easily be had, 5 as may be necessary from time to time. This construction the present device has in common with prior devices of the same kind. By having the wheel or its ring and floats or buckets extended down within the draft-tube 10 or arranged therein, as represented, the water is enabled to escape downward from the wheel, and its buckets are sustained to great advantage.

The chamber c^2 in the step g is provided 15 with two series of holes, d^2 and e^2 , leading out of it, as shown, the lower series being at the bottom and the upper series being at or near the top of the chamber. Water, while being discharged from the wheel, flows through the 20 upper holes into the chamber and out of it through the lower holes, and in so doing keeps the bearing-surfaces of the step and pivot from becoming heated by friction of one on the other. The lower edge of the feet or guides 25 of the gate are curved, as shown, to direct the water to advantage between the chutes.

In the above-described turbine I claim—

1. The combination of the water-wheel, its chutes and gate, its surrounding case, with the packing-ring k' , having on its outer edge a 30 tongue, the ring b' , with its groove m' , for the tongue of ring k' , and the upper grooved packing-ring, o' , secured to ring k' by screws, all substantially as and for the purpose described. 35

2. The combination of the shaft a , the step g , having its chamber c^2 , with upper and lower holes, the saucer-shaped bearing-plate q' , and wooden step-piece h , having a water-channel, p'' , supported in the vertically-adjustable socket i , as and for the purpose described. 40

3. The combination of the water-wheel and its case and shaft, provided with the iron collar and its wooden bearing, as described, with the step g , having the chamber c^2 , furnished with upper and lower holes, as set 45 forth, the saucer-shaped plate q' , and wooden step-piece h , having a water-channel, p'' , as and for the purpose specified.

NELSON ELVIRUS HARRIS.
